WELL MECHANISM

Filed Feb. 15, 1926

UNITED STATES PATENT OFFICE.

GROVER C. BUSHONG, OF WHITTIER, CALIFORNIA.

WELL MECHANISM.

Application filed February 15, 1926. Serial No. 88,259.

It is the object of this invention to provide extremely simplified but practical means for preventing unscrewing of the lengths of a string of sucker rods which operates the pump 5 of a well, the improved construction being readily adaptable to standard well pumping mechanism without replacing or altering the pump mechanism.

It is a further object of the invention to 10 provide a construction forming both a tubing bleeder and a means for preventing unscrewing of the sucker rods.

The invention will be readily understood 15 from the following description of the accompanying drawings, in which:

Fig. 1 is an axial section through a well tubing showing the improved construction, the tubing bleeder being closed.

Fig. 2 is a similar view showing the tubing 20 bleeder open.

Fig. 3 is a transverse section on the line 3—3 of Fig. 1.

In the drawings a usual string of well tubing is shown as comprising lengths of 25 tubing 1 connected by coupling collars. A string of sucker rods reciprocates in the tubing and is adapted to operate standard deep-well pumping mechanism which includes plunger 2 having the usual working 30 valve 2^a and connected to the string of sucker rods for reciprocation in the usual working barrel 1^a which depends from the string of tubing. The joints between the sucker rods and the connection for the pump plunger are 35 usual coupling collars adapted for threaded engagement with projecting pins on the sucker rods and on the pump plunger.

The coupling collar 3 between the pump plunger and the lowermost sucker rod 4 is 40 preferably locked, as for example by transverse wedges 5 extending through the coupling collar and the projecting pins which are threaded into the same; and the lowermost sucker rod is held against turning in 45 the well tubing, so that with the upper end of the string of sucker rods also held against turning by its usual connection with a walking beam (not shown), unscrewing of any of the joints of the sucker rod is prevented.

In order to hold the lowermost sucker rod 4 against turning in the tubing, it is non-circular in cross-section and reciprocates 55 through a corresponding axial bore in a member which is entirely independent of the pump plunger and its working barrel and is adapted to wedge in the tubing for use in

conjunction with standard pumping mechanism without altering or replacing the latter. The wedging member preferably seats in a tapering bore 7 formed in one of the coupling 60 collars between adjacent lengths of the well tubing. This coupling collar which is shown at 8 has the adjacent lengths of tubing threaded thereto with an intermediate portion of the internal peripheral surface of the 65 collar spacing the proximate ends of the connected lengths of tubing and forming the tapering bore 7 which convergently tapers downwardly to a somewhat smaller diameter than the internal diameter of the well tubing. 70 The wedging member may comprise cooperating segments 9 and 10, the meeting edges of which are angularly disposed relative to its axis as shown at 11, so that lowering the segment 9 relative to segment 10, will expand the 75 segmental members and wedge the same in tapering bore 7. To release the segmental members from wedging engagement, segment 9 is elevated relative to segment 10, thereby contracting the parts, due to the inclination 80 of meeting edges 11.

The means for elevating segment 9 comprises an extension thereof terminating in a plate 12 which underlies the segment 10 in spaced relation therefrom, so that withdrawal 85 of the string of sucker rods from the well will cause coupling collar 3 to impinge against the plate 12 and first elevate segment 9 relative to segment 10 in order to break the wedging engagement in bore 7, and then elevate 90 both segments of the wedging member by the abutment of plate 12 against the segment 10.

In order to permit expansion and contraction of the wedging member while preventing complete disengagement of the segments, the 95 upper end of segment 9 preferably tapers upwardly to a somewhat restricted diameter as shown at 15, and a closed annulus 16 at the upper end of segment 10 is received over the tapering end of the cooperating segment.

The lowermost sucker rod 4 is shown as square in cross-section, and the axial bore 18 of the wedging member through which the sucker rod reciprocates, is similarly rectangular to permit free sliding of the sucker rod 105 therethrough while preventing turning of the sucker rod. The bore 18 is continued through the plate 12 and is transversely elongated in the direction in which segments 9 and 10 expand and contract, to permit said action of 110 the segmental member without binding thereof on the sucker rod.

Ports 20 also open axially through the segmental member to permit free flow of oil when the member is wedged in bore 7.

The segmental member 9—10 is held against turning in the well tubing by its wedging engagement in bore 7, and the sucker rod 4 is held against turning in the segmental member by its reciprocation through bore 18. The lower end of the string of sucker rods fixed 10 against turning relative to the pump by the locking means 5, and the upper end of the string of sucker rods is non-rotatably held by its connection with the walking beam of the pump, and as a consequence various lengths 15 of the string of sucker rods are held against relative turning, and unscrewing of any of the joints is thus prevented.

If desired, the wedging member seating in bore 7, may also function as a tubing bleeder. 20 For this purpose a port 25 opens through coupling 8 at the bore 7, and when the segmental member is wedged in the bore it closes the port as shown in Fig. 1. The port is opened to permit bleeding of the tubing by 25 lifting the string of sucker rods so that coupling 3 impinges against the plate 12, thereby releasing the wedging engagement of the segmental member and then elevating the same as previously described and as shown in Fig. 2.

It will be apparent that the segmental wedging member will prevent unscrewing of the sucker rods with or without the additional feature of the tubing bleeder formed by port 35 25; and that means other than the segmental construction 9—10 may be non-rotatably held in the tubing to prevent turning of the sucker rod and also open and close the bleeder port when the latter is included in the construction.

40 Anti-friction means may be provided between the sucker rod 4 and the segmental members 9—10, and as an instance of this arrangement ball-bearing 19 may be journaled in the walls of the bore 18 so as to project into the bore and engage the reciprocating sucker rod.

I claim:

1. The combination of a string of sucker rods and a member comprising axial sections 50 having abutting edges adapted to radially expand or contract the member by relative axial movement between the sections, said member having a bore adapted to receive one of the sucker rods therethrough, and the bore and 55 sucker rod having a cross-sectional shape preventing rotation while permitting reciprocation of the sucker rod relative to the sectional member.

2. The combination of well tubing, a string 60 of sucker rods adapted to reciprocate in the tubing, and a split member adapted for wedging engagement in the tubing, said split member having a bore adapted to receive one of the sucker rods therethrough, and said bore 65 and sucker rod having a cross-sectional shape

70 preventing rotation while permitting reciprocation of the sucker rod relative to the split member.

3. A split member adapted for wedging engagement in a string of well tubing and having a bore non-circular in cross-section adapted 75 for reception therethrough of a sucker rod of corresponding cross-sectional contour so as to permit reciprocation of the sucker rod and prevent rotation thereof relative to the split member.

4. The combination of a string of well tubing, a string of sucker rods adapted to reciprocate in the well tubing, a collar having an integral peripheral surface spacing proximate ends of connected lengths of the well tubing and forming a bore convergently tapering toward its lower end to a diameter less than the internal diameter of the well tubing, and a member adapted for axial wedging engagement 80 in said tapering bore and adapted to engage one of the sucker rods so as to prevent relative rotation while permitting relative reciprocation of said sucker rod.

5. The combination of a string of well tubing, a string of sucker rods adapted to reciprocate in the well tubing, a collar having an integral peripheral surface spacing proximate ends of connected lengths of the well tubing and forming a bore convergently tapering toward its lower end to a diameter less than the internal diameter of the well tubing, and a member adapted for insertion or withdrawal through the string of well tubing and 85 adapted for axial wedging engagement in said tapering bore, said member when wedged in the tapering bore being adapted to engage one of the sucker rods so as to prevent relative rotation while permitting relative reciprocation of said sucker rod.

6. The combination of a string of well tubing, a string of sucker rods connected by coupling collars and adapted to reciprocate in the well tubing, a collar having an integral peripheral surface spacing proximate ends of connected lengths of the string of well tubing and forming a bore convergently tapering toward its lower end to a diameter less than the internal diameter of the well tubing, a member adapted for axial wedging engagement 100 in said tapering bore, said wedging member having a bore adapted to receive one of the sucker rods therethrough with said bore and sucker rod of a corresponding cross-sectional shape preventing rotation while permitting reciprocation of the sucker rod relative to the wedging member, and the wedging engagement of the wedging member being

110 adapted for release by axial abutment of the sucker rod coupling collar which is below the wedging member.

7. A combination of a string of well tubing, a collar having an integral peripheral surface spacing proximate ends of connected lengths of the string of well tubing and form- 120

ing a bore convergently tapering toward its lower end to a diameter less than the internal diameter of the well tubing, a member adapted for axial wedging engagement in said tapering bore, a string of sucker rods adapted for reciprocation in the well tubing and connected by coupling collars adapted for disengagement by relative turning of the sucker rods, a pump plunger, detachable means for connecting the lowermost sucker rod to the pump plunger, and means for positively locking said connection against disengagement, the said wedging member having a bore and being so positioned in the string of well tubing as to receive the lowermost sucker rod therethrough with said lowermost sucker rod and bore of a corresponding cross-sectional shape preventing rotation while permitting reciprocation of the sucker rod relative to the wedging member.

8. The combination of a string of well tub-

ing, a string of sucker rods adapted to reciprocate in the well tubing, a collar having an integral peripheral surface spacing proximate ends of connected lengths of the well tubing and forming a bore convergently tapering toward its lower end to a diameter less than the internal diameter of the well tubing, a member adapted for axial wedging engagement in said tapering bore and having a bore adapted to receive one of the sucker rods therethrough, and anti-friction means between said sucker rod and the bore of the wedging member, said bore of the wedging member and the said sucker rod being of a corresponding cross-sectional shape preventing rotation while permitting reciprocation of the sucker rod relative to the wedging member.

In testimony whereof he has affixed his signature to this specification.

GROVER C. BUSHONG.
